(57) **CLAIM**

The ornamental design for a “barrel for a hair dryer,” as shown and described.

DESCRIPTION

FIG. 1 is a top perspective view of a barrel for a hair dryer, showing our new design;

FIG. 2 is a front elevational view of the barrel for a hair dryer shown in FIG. 1;

FIG. 3 is a back elevational view of the barrel for a hair dryer shown in FIG. 1;

FIG. 4 is a right side elevational view of the barrel for a hair dryer shown in FIG. 1;

FIG. 5 is a left side elevational view of the barrel for a hair dryer shown in FIG. 1;

FIG. 6 is a top plan view of the barrel for a hair dryer shown in FIG. 1;

FIG. 7 is a bottom plan view of the barrel for a hair dryer shown in FIG. 1; and,

FIG. 8 is a bottom perspective view of the barrel for a hair dryer.

The subject matter shown in dashed lines is for illustrative purposes and forms no part of the claimed design.
